NOZZLE LOCK

Homer D. Moser, Fort Wayne, Ind., assignor to
 The Wayne Pump Company, Fort Wayne, Ind.,
 a corporation of Maryland

Application May 19, 1951, Serial No. 227,265

1 Claim. (Cl. 248—75)

1

This invention relates to a new and improved nozzle lock and more particularly to a lock for retaining nozzles of gasoline dispensing systems for unauthorized removal from the dispensing housing or casing.

In usual types of dispensing pumps for gasoline or similar liquids it is customary to provide a dispensing hose with a metal nozzle thereon. This nozzle contains a manually operable shut off valve and may contain other control units. The hose leads from the housing which contains the pump, together with the meter and counter or computer units. This housing is provided with a recess which serves as a receptacle for holding the nozzle when it is not in use. This receptacle usually contains a movable nozzle plate by means of which inserting the nozzle in the recess and removing it therefrom serves to operate certain interlocks on the operation of the dispensing pump. These interlocks are usually required by law in that they insure that a dispensing operation cannot be started without setting the counter back to zero.

The usual type of construction provides only an exposed padlock to prevent unauthorized removal from its housing. If the main control switches are on, the dispensing apparatus may be operated to deliver liquid by operation of the nozzle controls when the nozzle is removed from the housing and from engagement with the nozzle switch plate so that in the absence of an attendant, it would be possible for an unauthorized person to secure a delivery of liquid. Even when the main switches are opened, as when a station is closed for the night, it is highly undesirable to permit unauthorized persons to remove a nozzle from its housing. The nozzle and hose may be stolen or intentionally damaged or may be left where it may be damaged or be a hazard to traffic.

It is an object of the present invention to provide a new and improved nozzle lock for dispensing equipment.

It is a further object to provide such a lock which positively retains the nozzle in its normal storage or non-use position.

It is also an object to provide a nozzle lock which is operable only from the inside of a dispensing housing and hence only by the possessor of a key to the housing.

It is an additional object to provide such a lock which is simple in design and operation and designed for commercial production and use.

Other and further objects will appear as the 55 description proceeds.

2

Figure 1 is a fragmentary face view, partly in section, showing the lock construction;

Figure 2 is a fragmentary side elevation of the construction of Figure 1 also partly in section; and

Figure 3 is a horizontal transverse section through the constructions of Figures 1 and 2.

In the drawings, a dispensing housing 11 is shown as having a nozzle receptacle 13 secured thereto. This receptacle 13 comprises a lower recess 15 and an upper pocket 17 into which the upper end 19 of the nozzle 21 is fitted. The particular construction of the nozzle 21 forms no part of the present invention, but the nozzle is provided with the usual guard member 23 and valve operating lever 25, as shown in broken lines in Figure 2.

The nozzle hook 27 is secured in the lower portion of the receptacle 13 by means of the bolt 28 and nut 30. This nozzle hook 27, as best shown in Figure 2, is provided with a perforation 32 for the reception of the locking pin 34. The nozzle switch lever 36 is pivoted on member 38 which is held in place by nut 40 in the rear wall of the nozzle receptacle 13. As shown in Figure 3, the lower portion 42 of the nozzle lever 36 is bifurcated so that it extends down on either side of the nozzle hook 27. The nozzle lever 36 has the rod 44 pivotally connected thereto, this rod extending through the rear wall of the nozzle receptacle 13. It will be understood that this rod 44 is connected to the usual type of interlock mechanism and particularly to the switch for controlling the pump motor of the dispensing apparatus. This particular construction is well known in the art and will not be described in detail since it forms no part of the present invention.

The lateral wall 50 of the nozzle receptacle 13 is thickened in the form of a conical boss at 52 in order to give greater support to the locking pin 34. This locking pin has an enlarged head 54 and the compression spring 56 which is fitted around the pin 34 bears against the underside of head 54 and against the outer face of the side wall 50 of the receptacle 13 so that it normally urges the pin 34 outwardly of the receptacle and holds it in the unlocked position, as shown in Figures 1 and 3 of the drawings.

50 The angle member 58 may be one of four such members forming the supporting frame for the pump, meter, counter and other internal mechanism of the dispensing apparatus. The pivot pin 60 passing through the angle member 58 serves as a pivoted support for the locking pin

lever 62. As best shown in Figure 3, this lever 62 is U-shaped in cross section and has a laterally extending actuating arm 64 from which extends a finger piece and latch member 66. The lower portion of the lever 62 engages the outer face of the enlarged head 54 of pin 34, as clearly shown in Figure 1. A projection 68 formed on the lower portion of member 62 engages the angle member 58 to limit the counter-clockwise movement of the lever under the influence of the locking pin spring 56 so that the pin is retained in position in the boss 52 in the nozzle receptacle 13.

It will be noted from Figures 2 and 3 that the lever 62 has a limited sliding movement on the pivot pin 60, this movement being at right angles to the movement of pin 34. The lock is placed in locking position by moving the finger piece 66 downwardly and sliding the lever 62 to the left on pin 60, as seen in Figure 2, until the upper edge of finger piece 66 fits under the shoulder 70 with the lever in the broken line position of Figure 1. In this position the locking pin 34 will be forced inwardly of the housing 13 and through the perforation 32 in the nozzle hook 27. In this position the locking pin 34 will also be within the guard 23 of the nozzle so that it is impossible to lift the nozzle or pull it out sufficiently to clear the housing 13. The upper part of the nozzle 19 cannot be swung outwardly since it is held in the pocket 17. As shown in Figure 1, the lower portion of the guard member 23 is divided to fit over the hook 27 as it is moved back against the nozzle lever 36.

As shown in Figure 3, the housing 11 is provided with a door 72 which may be supported at its opposite edge on a hinge which has not been shown. This door 72 carries the lock 74 having a locking lug 76 adapted to engage behind the edge of the housing member 11 when the housing is locked. The operating lever 62 and its finger piece 66 are completely enclosed within the housing and cannot be operated to unlock the nozzle until the door 72 is unlocked and opened. Consequently, it is impossible for the lock to be released except by an authorized per-

son having a key to the housing. This is accomplished without the use of an additional lock and the locking mechanism is concealed and enclosed.

While I have shown certain preferred embodiments of my invention, these are to be understood to be illustrative only as it is capable of variation to fit different structures and to meet differing conditions and requirements, I therefore contemplate such modifications as come within the spirit and scope of the appended claim.

I claim:

A nozzle lock for dispensing apparatus comprising a housing having a recessed nozzle receptacle, a nozzle hook within the receptacle and a nozzle having a valve lever guard frame fitting adjacent the nozzle hook, the nozzle hook and a lateral wall of the nozzle receptacle being formed with aligned openings, the opening in the nozzle lock being within the nozzle guard frame when the nozzle is seated in the receptacle, a lock pin having an end normally within the receptacle wall opening, the pin extending outwardly of the receptacle within the housing, a spring normally urging the lock pin away from the receptacle, a pivoted lock pin actuating lever within the housing, said lever engaging the pin, a stop for limiting movement of the lever to hold the end of the pin in the receptacle wall opening, the lever having an arm for moving the lever to force the lock pin into the receptacle housing and into the nozzle hook opening to lock the nozzle against removal, and means engaging the lever arm for holding the lock pin in locked position.

HOMER D. MOSER.
